Atty.

Witness:

Dave S. Magnusson.

UNITED STATES PATENT OFFICE

KENNETH E. LYMAN, OF CHICAGO, ILLINOIS, ASSIGNOR TO BENDIX BRAKE COMPANY,
OF CHICAGO, ILLINOIS, A CORPORATION OF ILLINOIS

BRAKE-OPERATING MECHANISM

Application filed May 5, 1927. Serial No. 188,976.

This invention relates to shaft supports, and is illustrated as embodied in a novel simplified support for the chassis end of a shaft operating a front-wheel brake.

Preferably the support includes only two simple parts, shown as stampings, one being a stationary member which may be carried by the chassis frame and which has an outwardly-spherical portion formed with a relatively large opening, and the other being a movable member having a shaft-embracing sleeve projecting through the opening into the interior of the stationary member.

A spring tensioned between the sleeve and the stationary member urges an interiorly-spherical shell, forming part of the movable member, against the above-described outwardly-spherical portion. Thus the entire support consists of two simple stampings and one spring.

The above and other objects and features of the invention, including various novel and desirable details of construction, will be apparent from the following description of one illustrative embodiment shown in the accompanying drawing, in which:

Figure 1 is a vertical transverse section through one front brake and associated parts;

Figure 2 is a section on the line 2—2 of Figure 1, showing the novel support in outside elevation; and

Figure 3 is a section on the line 3—3 of Figure 1, showing the novel support in inside elevation.

The illustrated brake includes a drum 10, rotating with a wheel (not shown) on the spindle 12 of a knuckle 14 swivelled, by a king pin 16 or the like, at the end of a front axle 18 supporting a chassis frame 20 through the usual springs 22. A support such as a backing plate 24 carried by the knuckle 14 is arranged at the open side of drum 10.

The brake proper includes shoes 26 within the drum 10, and controlled by means such as a cam 28 operated, through a universal joint 30 above the king-pin 16, by a shaft 32. Shaft 32 may be rocked, to apply the brake, by suitable means such as an arm 34.

According to an important feature of the present invention, the chassis frame 20 or its

equivalent is provided with a novel simplified support for the end of shaft 32, the illustrated support permitting the shaft to move endwise and to rotate, and also to move angularly crosswise of its axis to compensate for movements due to flexing of spring 22.

In this particular arrangement, the end of the shaft is slidably embraced by a sleeve 36 carried by, or integral with, a shell 38 which is interiorly-spherical and which slidably engages an outwardly-spherical portion 40 on a stationary member 42 secured by bolts 44 to the chassis frame 20.

The outwardly-spherical portion 40 faces away from the chassis frame 20, and is formed with a relatively large central opening through which the sleeve 36 projects into the interior of the stationary member 42.

The shell 38 is urged against the outwardly-spherical portion 38 by a spring 46 tensioned between sleeve 36 and member 42. In the illustrated arrangement, a flange 48 spun on the end of sleeve 36 is engaged by one end coil of spring 46, and a ledge 50 pressed in member 42 is engaged by the other end 75 coil of spring 46.

While one illustrative embodiment has been described in detail, it is not my intention to limit the scope of the invention to that particular embodiment, or otherwise than 80 by the terms of the appended claims.

I claim:

1. A support for the chassis end of a brake-operating shaft comprising, in combination with the shaft, a chassis-supported member having an outwardly-spherical portion directed away from the chassis and formed with a relatively large opening, an interiorly-spherical shell slidably engaging said outwardly-spherical portion and having a sleeve embracing the end of the shaft and projecting through said opening to the interior of the chassis-supported member, and a spring tensioned between the sleeve and the chassis-supported member and urging the shell against the outwardly spherical portion.

2. A shaft support comprising, in combination with the shaft, a stationary member having an outwardly-spherical portion

formed with a relatively large opening, an interiorly-spherical shell slidably engaging said outwardly-spherical portion and having a sleeve embracing the shaft and projecting through said opening to the interior of the stationary member, and a spring tensioned between the sleeve and the stationary member and urging the shell against the outwardly spherical portion.

- 10 3. A shaft support comprising, in combination with the shaft, a stationary member having an outwardly-spherical portion formed with a relatively large opening, an interiorly-spherical shell slidably engaging said outwardly-spherical portion and having integrally formed therewith a sleeve embracing the shaft and projecting through said opening to the interior of the stationary member, and means tensioned between the sleeve and the stationary member and urging the shell against the outwardly spherical portion.
- 15 4. A shaft support comprising, in combination with the draft, a stationary member having an outwardly-spherical portion formed with a relatively large opening, an interiorly-spherical shell slidably engaging said outwardly-spherical portion and having a sleeve embracing the shaft and projecting through said opening to the interior of the stationary member, and a spring tensioned between a flange on the sleeve and a step portion on the stationary member and urging the shell against the outwardly-spherical portion.
- 20 35 In testimony whereof, I have hereunto signed my name.

KENNETH E. LYMAN.
